UNITED STATES PATENT OFFICE.

WILLIAM FEICKS, OF BLOOMFIELD, NEW JERSEY.

PROCESS OF OBTAINING BY-PRODUCTS FROM THE GASEOUS DISTILLATION OF FUELS.

1,051,876.

Specification of Letters Patent.

Patented Feb. 4, 1913.

Application filed February 14, 1912. Serial No. 677,645.

To all whom it may concern:

Be it known that I, WILLIAM FEICKS, a subject of the German Emperor, residing at Bloomfield, in the county of Essex and State of New Jersey, have invented new and useful Improvements in Processes of Obtaining By-Products from the Gaseous Distillation of Fuels, of which the following is a specification.

10 This invention relates to processes of obtaining by-products from the gaseous distillation of fuels, and more particularly to improved methods of manufacture of ammonium sulfate from distillation gases, and especially gases from coke ovens, gas retorts and the like.

In processes for the manufacture of ammonium sulfate from distillation gases heretofore known, the gases from coke ovens, gas furnaces and the like are usually cleaned and cooled so as to condense tar and water, after which they are either directly or in a superheated state conducted into a sulfuric acid bath for the formation of ammonium sulfate. Or, according to other known methods, the first quantities of gases from the retorts or coke ovens containing the greater part of tar yield are divided from the latter quantities of the gases containing relatively little or no tar, and are freed from tar, then combined with the latter quantities and passed to the acid bath.

An objection to the first mentioned process is that the whole of the ammoniacal liquor from the gases is condensed in cooling such gases to eliminate tar and water and thus comparatively large apparatus is necessary for the cooling and extracting step, since, as stated, the whole of the gases evolved by the ovens are sent through the apparatus. Furthermore, the superheating of the gases after they have been cooled requires special apparatus, and this is a serious objection from the manufacturing standpoint and tends to increase the cost of manufacture. In the second named above process, no superheating of the gas is effected, as it has been found that while in most cases the heat transmitted to the acid saturation bath, due to the chemical reaction between the ammonia and acid, may suffice to keep the bath at a sulfate-forming temperature, this process cannot be carried out under all conditions, for there may not

be sufficient self-generating heat in the bath and the gases may be below the correct temperature for efficient operation of the process. Also, it frequently happens that the gases contain relatively large quantities of fixed ammonia, whose heat of reaction with sulfuric acid is relatively small, in which event additional heating means should be employed. There are also a few other factors governing the above, so that the superheating of the gases before conducting them into the saturation bath cannot be altogether dispensed with.

According to the last named known process, there are no cooling or reheating steps, and there also being no condensates to be treated in stills, difficulties have been encountered in efficiently removing the tar from the oven gases at high temperature, even with a tar injector. If, on the other hand, according to the process now under discussion, the first and larger quantities of gases from the retorts or ovens are cooled and thus freed of their tar, upon the combination of such tar-free gases with the latter withdrawn gases further condensates are very likely to form. The processes above mentioned cannot be readily adapted to economically operate the plant to advantage by employing the poorer gases evolved by the ovens for heating the same and the rich gases for the market.

The objects of my invention are to eliminate the several objections above pointed out in the hitherto known processes; to produce ammonium sulfate in a continuous, cheap and commercially successful manner; to provide a process of making ammonium sulfate, which process may be performed with the aid of smaller and thus cheaper apparatus; and to generally more economically and effectually recover the by-products from the gases than has been hitherto accomplished through any known process.

With these and other objects in view, my invention comprises withdrawing distillation gases evolved during the first part of the coking period and containing the greater part of tar yield separately and distinct from the latter quantities of gas containing little or no tar, cooling the first quantities to condense tar and gas water, and simultaneously but separately conducting both quantities of gases into the same

acid saturation bath and separately withdrawing both quantities of gas from the bath for use in heating the retorts or ovens and for market purposes. In this manner all disadvantages of the previous named processes are obviated, there being no super-heating of the cooled gases necessary, since the latter quantities of gases which enter the bath at a comparatively high temperature serve to maintain such temperature of the bath that the salt is easily and effectually formed; the apparatus for cooling the gases can be of much smaller capacity and the quantities of gas water to be heated in the stills correspondingly less. The differences in temperature in the bath created by conducting the gases of different temperature into the bath serve to keep the bath in constant motion, thus advantageously influencing the formation of salt. And as stated, the rich and poorer gases are recovered separately with the least possible outlay for duplicate apparatus and cost of operation.

The accompanying drawings illustrate diagrammatically one form of a plant for carrying out my processes in connection with coke ovens.

In the drawings, 1 represents a battery of coke ovens or gas furnaces, shown in a longitudinal, irregular section, B being the forward end of one oven and A the rear end of another oven. Each oven is periodically filled and discharged as usual. During the first part of the coking period the gases of distillation, being of a higher calorific value and containing all or the greater part of the tar yield from the oven charge, are drawn off from ovens lettered A (for instance) through standpipes 2 (provided for each oven) into the gas main 3 which connects all of the similar standpipes of the ovens. From the gas main the gas is conducted through pipe 4 into the tar drag 5, in which most of the tar is removed in the well known manner. From the drags the gases are conducted by pipe 6 into coolers 7, from whence they are drawn by pipe 8 into blower 9 which in turn forces such gases through tar extractor 10 where the last traces of tar are removed. After these gases are thus cooled and freed of their tar (and incidentally of a small part of their ammonia), they are without reheating conducted directly into the saturation vessel 12, through pipe 11, the saturation vessel containing sulfuric acid or an acid salt solution. The preferred temperature of the gases flowing through pipe 11 lies between approximately 10° and 20° centigrade, but, of course, the invention is not to be limited to operation upon gases of these specific temperatures. The saturation vessel here shown is of novel construction and is not claimed here, but is to form the subject-matter of an application soon to be

filed by me. The gases from pipe 11 enter 65 the annular subchamber 13. In passing through the absorption lye the gases give up their ammonia to the acid and collect in the top part of the vessel 12 above the bath, from whence they are led away by pipe 14 70 to be used for illuminating purposes or consumed in gas engines, or the like.

Simultaneously with the above, the gases of distillation of other furnaces (for instance B) comprising the battery of ovens 75 and whose coal charges are in their last stages of carbonization and are giving off a poor gas practically free of tar, are conducted through the standpipes 15, one of which is provided for each oven, and into 80 the main 16 which runs along the length of the battery. These gases are conducted by pipe 17 to the suction device 18, which, as illustrated, is a tar injector. The tar injector has for its object to remove any traces 85 of tar which may be left in these gases. In cases where such gases contain very little or no tar so as to be unobjectionable, an ordinary blower may be used to the same advantage. The tar free and hot gases leave 90 the suction devices through pipe 19 to be forced directly into the saturation vessel 12 before referred to. The temperature of these gases when conducted into the saturation vessel is preferably kept slightly above 95 the condensation point of the gases, which is about 70° C. for retort gases and 80° C. for coke oven gases, the stated difference being due to coal used in gas works being practically free from moisture, while on the other hand the coal used in coke ovens is frequently dampened to produce a better quality coke. Any cooling means may be employed in this lean gas system to maintain such gases at the proper temperature if 100 they leave the ovens too hot for the purpose in view and when, for instance, it may be desirable to cool them below the dew point. The hot gases pass through the bath in the manner indicated by the arrows and collect 110 in the inner annular chamber 20, are conducted through pipe 21 into cooler 22 from whence they are returned by pipe 23 to the coke ovens to serve for heating purposes, if desired. If these gases, after passage 115 through the acid bath, are used for heating the ovens or retorts, the final cooling of such gases may, of course, be omitted. Ammonium sulfate formed may be removed from the saturation vessel 12 in any desired manner.

If the second and poorer quality of gases are obtained in excess of that required to heat the ovens, in connection with other heating means, the pressure regulator 24, 120 upon exceeding a certain pressure in the second system, automatically allows a larger or smaller quantity of gases to pass through

pipe 25, through regulator 24 and pipe 26, back into the first described system handling the richer gases, thus making the whole operation perfectly self-governing.

5 The quantities of gases sent through either system during the duration of a coking period depends upon the rapidity with which the coking of the charge progresses, and further on the temperature to be maintained in 10 the acid bath and some other factors, and may in different plants vary within wide limits.

The tar and other condensates from the tar drag 5, coolers 7, tar extractor 10 and 15 suction device 18, are conducted by a system of pipes into settling tank 27, from which the tar flows into tanks 28, and the gas water into tank 29. From this latter tank the gas water is lifted by pump 30 and forced in 20 still 31, where the ammonia may be drawn off in the usual manner with steam. The ammonia vapors mixed with the steam leave the still by pipe 32 and after being dried as usual in a condenser 33 are led by pipe 34 25 into pipe 19 and mixed with gas passing therethrough to the saturation vessel 12 or may be conducted direct to such vessel.

It is to be understood that a whole battery 30 of ovens may be operated upon at the same time, the rich gases from some of such ovens being conducted through one process, while the poorer gases from the other ovens in a different stage of carbonization are being conducted through the other process.

35 What I claim is:—

1. The process of manufacturing ammonium sulfate which comprises collecting coal gases rich in tar, cleaning the same of tar and water, cooling the same and passing 40 through sulfuric acid to form sulfate; and simultaneously but separately collecting gases less rich in tar, and passing through the sulfuric acid to heat the same and form sulfate, collecting the gases from said acid 45 separately; and collecting the ammonium sulfate formed.

2. In the manufacture of ammonium sulfate, the process which comprises simultaneously withdrawing from different sources, 50 ammonia containing gases of different compositions, passing one such gas through an acid to heat the same and form sulfate, simultaneously cleaning and cooling the other gas and passing it separately through 55 the same acid to form sulfate, and separately collecting said gases after passage through said acid.

3. In the manufacture of ammonium sulfate, the process which comprises simultaneously withdrawing from different sources 60 ammonia containing gases of different compositions, cooling and treating one such gas to separate tar and ammonia water therefrom, partially cooling the other gas and

treating it to remove tar, simultaneously 65 passing both gases through the same sulfate forming bath and separately withdrawing said gases from said bath.

4. In the manufacture of ammonium sulfate, the process which comprises simultaneously withdrawing from different sources, 70 ammonia containing gases of different compositions, one such gas containing a relatively large percentage of tar as compared to the other gas, cleaning and cooling the 75 gas containing the larger percentage of tar and passing the same through an acid bath to form sulfate, passing the other gas direct to the acid bath to heat the same and form sulfate, and separately collecting said gases 80 from the acid bath, after formation of the salt.

5. In the manufacture of ammonium sulfate, the process which comprises simultaneously withdrawing from different sources 85 ammonia containing gases of different compositions, cleaning one such gas of any tar and passing such gas without cooling to an acid bath to heat the same to form sulfate, and simultaneously cleaning and cooling the 90 other gas and passing it separately from the first mentioned gas into said acid bath to form an ammonium salt.

6. In the manufacture of ammonium salts from coke ovens or gas furnace gases, the 95 process which comprises withdrawing ammonia containing gases of different compositions from different ovens, passing one such gas through an acid bath to heat the same and to form a salt and burning such gas 100 under the furnaces, simultaneously cleaning and cooling the other gas and conducting it to the acid bath to form a salt and thence to a storage tank, and automatically passing gas of the first named composition into gas 105 of the second named composition, when consumption of the gas burning under the furnaces diminishes.

7. In the manufacture of ammonium sulfate, the process which comprises cleaning 110 and passing ammonia containing gases from one source through an acid bath to heat the same and form sulfate, simultaneously but separately cleaning, cooling and passing gases from another source through said acid 115 bath to form ammonium sulfate, collecting and separating the products cleaned from both gases, distilling a portion of them to recover ammonia, and conducting such ammonia into said acid bath to form sulfate. 120

8. In the manufacture of ammonium sulfate, the process which comprises treating an ammoniacal gas from one source to remove tar, and passing such tar-free gas through an acid bath to heat the same and form a sulfate; simultaneously but separately treating another ammoniacal gas from 125 a different source to form condensates in-

4
cluding tar and gas water, passing such gas to said acid to form sulfate collecting said condensates together with the tar removed from said first named gas, separating the tar from the gas water, distilling the latter to form ammonia and passing said ammonia to said acid bath to form sulfate.

In testimony whereof I have hereunto set my hand, in the presence of witnesses.
